UNITED STATES PATENT OFFICE.

CHARLES L. BRONK, OF BROOKLYN, NEW YORK.

SQUARE.

SPECIFICATION forming part of Letters Patent No. 435,086, dated August 26, 1890.

Application filed April 17, 1890. Serial No. 349,051. (No model.)

To all whom it may concern:

Be it known that I, CHARLES LEONARD BRONK, of Brooklyn, in the county of Kings, in the State of New York, have invented a new and useful Improvement on a Carpenter's Steel Square; and I do hereby declare that the following is a full, clear, and exact description of the construction and operation of the same, reference being had to the annexed drawings, making a part of this specification.

My invention relates to an improvement in steel squares, in which the arms are pivotally secured together, so that one may be swung with relation to the other throughout an arc of ninety degrees.

The object is to so construct the joint between the two arms that the strain upon the pivotal point may be materially reduced and a bearing of such extent formed that there will be little or no liability of the arms wearing so as to be thrown out of a true perpendicular to each other when opened, and to further provide for a true lateral seat of the two arms and for automatically locking them in opened adjustment.

With these ends in view my invention consists in certain features of construction and combinations of parts, as will be hereinafter described, and pointed out in claims.

A practical embodiment of my invention is shown in the accompanying drawings, in which—

Figure 1 is a view of the square in side elevation, the arms being broken and shortened in order to show the joint upon a larger scale. Fig. 2 is a view of the joint portion of the square in side elevation upon the reverse side from Fig. 1, the arms in Figs. 1 and 2 being shown as in extended adjustment. Fig. 3 is a view of the joint and portions of the arms contiguous thereto in side elevation, showing the position of the joint when the arms are partially opened; and Fig. 4 is a transverse section through line $\alpha\alpha$ of Fig. 1.

A represents the wider and longer of the two arms, and B represents the narrower and shorter of the two arms, of a square of the general form in common use. The two arms A and B are here shown graduated for a short distance from the joint only; but it is in-

tended that they shall be graduated throughout their entire lengths, as is common.

The arm A is provided with a shallow recess a , extending for a considerable distance 55 from its end, somewhat more than twice the width of the arm B, and terminating at its lower end in a curve a' , corresponding to a quarter of the circumference or more. This curved portion is provided with graduated 60 division-marks to designate the different angles from one degree to ninety degrees and subdivisions thereof, as may be desired. Said recess a occupies two-thirds or more of the width of the arm A, thereby forming not only 65 an elongated bearing in the direction of the length of the arm A, but also an extended bearing widthwise of the same.

The wall of the recess a is provided with an under-cut a^2 , extending throughout both 70 its curved and straight portions. The end of the arm A is further cut away along the edge of the recess a toward the arm B, forming an elongated notch, as shown at a^3 , the said notch terminating in a curved lower portion 75 a^4 . The edge of the notch a^3 throughout both its straight and curved portions is beveled to enter a corresponding under-cut, as will hereinafter appear.

The arm A is provided on its opposite face 80 from that on which the recess a is located with an elongated shallow recess a^5 for the reception of a flat bar-spring C. The portion a^6 of said recess a^5 near the end of the arm A extends through the arm A into the recess 85 a , hereinbefore referred to, for the reception of the nose c of the said spring C, which nose c projects through the said portion a^6 and forms a lock to secure the member or arm B in its extended adjustment with relation to 90 the arm A. I prefer to form the nose c of substantially rectangular shape, as shown, and bevel one of its corners, as shown at c' , for the purpose of gradually forcing it backward by the opening movement of the arm B. 95 The spring C is secured with its back flush with the surface of the arm A conveniently by means of a pair of short screws c^2 . It is intended that the recess a in the arm A shall have a depth equal to about one-half the 100 thickness of the arm A.

The arm B is provided on its end toward

the arm A with a plate b, of substantially the shape and thickness of the recess a, hereinbefore referred to, and its edge b' throughout both the straight and curved portions is 5 beveled to correspond to the under-cut hereinbefore referred to in the wall of the recess a. The plate b is further provided with a lateral projecting portion b², corresponding in shape and thickness to the notch or cut-away 10 portion a³ in the arm A, and is provided along the straight and curved portions of its edge with an under-cut b³, adapted to receive the beveled edge a⁴ of the notch a³. I find it convenient, as herein shown, to form the plate 15 b and the projection b² integral with the arm B.

The plate b is provided near its upper end with an opening b⁴, adapted to receive with a close fit the nose c of the spring C. I further 20 provide the beveled edge b' of the plate b with an oblique shoulder b⁵ at the point where it first engages with the nose c of the spring C, for the purpose of gradually depressing the spring out of the way of the plate b as it slides 25 into position within the recess a without the necessity of operating the spring by the pressure of the hand. The arm B is pivotally secured to the arm A by means of a pivotal screw or other suitable pivotal connection D, 30 which extends through the plate b near its lower or curved edge and a considerable distance back from the front or inner edge of the arm A and the plate b.

Between the pivotal connection D and the 35 curved end of the plate b in the form of my invention shown there is provided a curved closed-end slot E through the end of the plate b. A set-screw d extends through the curved slot E into the arm A, preferably with its 40 head flush with the face of the plate b. It will be observed that the two arms A and B when thus assembled have an extended bearing one upon the other and upon opposite

sides of the arm A, tending to prevent any displacement of the relative position of the 45 two arms when under strain. It will also be observed that the point where the nose of the spring locks the two arms together is at such a distance from the pivotal point of the two arms that the said arms are effectually locked 50 against any liability of displacement when under strain in a direction to close them.

What I claim as my invention is—

1. The combination, with the arms of a square, the one provided with an elongated 55 shallow recess and the other with an elongated thin plate corresponding to said recess, of a pivotal connection between the two arms at a considerable distance from the angle formed by the inner edges of the two arms, 60 and a locking device near the opposite end of said corresponding recess and plate from the pivotal connection, substantially as set forth.

2. The herein-described square, one of the arms being provided with an elongated wide 65 shallow recess a, having a curved end, and the other with a plate corresponding in shape and thickness to said recess, a pivotal connection between the two arms at a point near the said curved ends, one of the arms being 70 provided with a curved slot and the other with a set-screw extending within the curved slot, a spring seated in the arm provided with a shallow recess and having its nose projected within the recess to engage an opening 75 in the opposite arm, the two arms being further provided the one with an elongated notch and the other with an elongated lateral projection to correspond with the notch and located upon the opposite side of the square 80 from the recess and plate hereinbefore referred to, substantially as set forth.

CHARLES L. BRONK.
